UNITED STATES PATENT OFFICE.

GUERNY H. COLE, OF FOREST HILLS, PENNSYLVANIA, ASSIGNOR TO WESTINGHOUSE TYPE COMPANY, A CORPORATION OF NEW YORK.

SLUG-CASTING MOLD.

Application filed April 9, 1925. Serial No. 21,760.

To all whom it may concern:

Be it known that I, RICHARD R. MEAD, a citizen of the United States, residing at Brooklyn, in the county of Kings and State 5 of New York, have invented certain new and useful Improvements in Slug-Casting Molds, of which the following is a specification.

This invention relates to typographical casting machines, such as linotype machines 10 of the general organization represented in U. S. Letters Patent to O. Mergenthaler, No. 436,532, wherein a melting pot is arranged to deliver molten metal into a slotted mold and up against a composed line of matrices 15 to produce a type bar or slug bearing on its edge type characters corresponding to the intaglio characters of the matrices. As these molds are usually constructed, the side walls of the mold slot or cavity are formed by a 20 bottom or body portion and an upper or cap portion, while the end walls are formed by two end portions or liners held in place between the body and cap portions. Ordinarily, the molds are made to produce slugs 25 not exceeding 30 ems in length, but for certain classes of work, such as advertising or book work, the molds are made to produce slugs running as high as 42 ems in length.

In the manufacture of the mold parts, 30 which are made of steel, it is essential to harden them, or at least those portions which form the mold cavity, in order to avoid the adherence of molten metal to the mold surfaces as well as to resist wear upon such surfaces during the ejection of the cast slugs. This hardening process necessarily sets up 35 internal stresses in the metal and gives rise to warping or distortion of the casting surfaces when the mold is in use. Thus, when the molten metal is injected into the mold, 40 the mold surfaces become quite hot, and the stresses, being relieved, tend to readjust themselves upon the subsequent cooling of the mold surfaces, causing the warping or distortion just referred to. As a result, and 45 particularly in the case of the larger molds, imperfect slugs are produced and, moreover, damage to the mold and to the trimming and ejecting mechanism oftentimes occurs. Such 50 warping or distortion is confined almost entirely to the body and cap portions of the mold (the liners being comparatively small) and is accentuated by reason of the peculiar

formation of these parts, which are made of irregular shape or contour and of non-uniform cross-section. 55

The present invention is intended to obviate the foregoing difficulties and contemplates an improved form of mold, whose side walls, although hardened as before, will 60 be effectively prevented from warping or twisting out of proper shape. To this end, it is proposed to construct the mold body, as well as the mold cap, in two sections, instead of in one integral piece, as heretofore, 65 the inner or base sections (which constitute the side walls of the mold slot) being hardened according to any of the well-known methods, and the outer sections (which constitute reinforcing members for the side 70 walls) being left in unhardened condition. In making up the mold body and the mold cap in such composite fashion, the inner base portions may be of substantially uniform thickness and cross-section, while the outer 75 reinforcing portions may be of any desired shape or cross-section, it being possible, as intended, to design the parts so that the completed mold will be substantially identical in form to the standard mold now in use. 80 In hardening the base portions, certain internal stresses will be set up therein as of course, but these inherent stresses, due to the reduced thickness and the more nearly uniform cross-section of the base portions, will 85 be materially less than before, and hence not so apt to cause warping or distortion of the mold surfaces during the slug casting periods. On the other hand, the outer reinforcing portions, which are not hardened, 90 will be free from internal stresses and consequently not subject to warping or distortion during the slug casting periods, so that when these reinforcing portions are applied to the base portions they will serve as rigid 95 supports therefor and maintain them in proper shape. In other words, even though the hardened base portions are inherently subject to warping in some degree, notwithstanding their reduced and uniform cross-section, such warping tendency will be resisted and overcome by the unhardened reinforcing portions which are not thus inherently subject to warping. 100

In the accompanying drawings, the invention 105 has been shown merely in preferred

form and by way of example and as applied to a particular type of mold, but obviously many variations and alterations may be made therein and in its mode of application, 5 which will still be comprised within its spirit. Generally speaking, it is to be understood that the invention is not limited to any specific form or embodiment except in so far as such limitations are specified in the claims.

10 Referring to the drawings:

Fig. 1 is a perspective view, partially disassembled, of the proposed mold;

Fig. 2 is a front elevation thereof, assembled;

15 Fig. 3 is a top plan view of Fig. 2; and

Fig. 4 is a vertical transverse section, taken on the line 4—4 of Fig. 2.

Although equally applicable to the ordinary unprocessed mold or to molds of other 20 sizes, the invention has been herein illustrated as applied to a 42 em mold of the recessed or head-letter variety. Generally, the mold proper comprises the body A, the cap B, and the intermediate liners C, D, 25 these parts being held together in assembled relation by posts E rising from the body A and engaging in notches formed in the opposite ends of the cap B. The cap B is formed as usual, with the longitudinal 30 groove B⁵ in its front face and on its under face with a series of transverse depending blocks or core sections B⁶ projecting into the mold slot or cavity. So far as described, the 35 parts may be the same as those embodied in any commercial mold of the recessed type and in themselves constitute no part of this invention.

According to the present invention, the 40 mold body A is made up of an inner hardened steel base portion A¹ constituting the lower side wall of the mold cavity, and an outer unhardened steel reinforcing portion A², the two sections having a machined fit and held together by clamping screws A³. 45 Likewise, the mold cap B is made up of an inner hardened steel base portion B⁴ constituting the upper side wall of the mold cavity, and an outer unhardened steel reinforcing portion B², the two sections also 50 having a machined fit and held together by clamping screws B³. In this latter instance, dowel pins B⁴ are or may be employed to assist in locating the parts in proper relation to each other. It may be noted that the 55 reinforcing portions A² and B² are of the customary form and outline, so that when the several parts are assembled, the entire mold structure is substantially identical in form and outline with the standard molds now in 60 use. Thus, in Fig. 2, the composite mold is shown as mounted in the customary aperture formed in the mold wheel or disc F and is held in place therein by means of the customary clamping screws F¹. On the other 65 hand, the inner base portions A¹ and B⁴,

which constitute the opposite side walls of the mold cavity, are of substantially uniform thickness and cross-section throughout.

As the mold is thus constructed, when the 70 base portions of the body and cap are heat-treated for hardening purposes, the stresses set up are substantially uniform and have less tendency to cause distortion or warping of the mold surfaces during the intermittent 75 slug casting operations. However, whatever tendency there may be to distortion or warping in use, such tendency is resisted and largely overcome by the attached unhardened reinforcing portions, which have 80 no internal stresses and which, therefore, are not subject to distortion or warping in use. While the hardening of the inner base portions may be carried out in some other way, it is proposed in the manufacture of the improved mold to make said portions of non-shrinkable tool steel and harden them by 85 quenching in an oil bath, an added advantage which comes from the composite structure of the mold cap and mold body.

It will be understood that in carrying out 90 the present invention, it is not absolutely essential that the reinforcing portions A² and B² be secured directly to the base portions A¹ and B⁴, although such arrangement 95 is preferred, as such reinforcing portions may be supported independently of the base portions, as for instance by the mold disc or wheel F, and then clamped tightly down upon the base portions. In such embodiment 100 of the invention, the reinforcing portions should be made adjustable in order to receive the base portions and to apply the necessary pressure thereto when the parts are brought together, as well as to permit 105 the separation of the base portions in changing the liners in varying the dimensions of the mold cavity. The broad invention in 110 this regard resides in a composite mold having hardened steel side walls and reinforcing 115 members applied to the side walls serving to resist warping or distortion thereof.

Having thus described my invention, its 115 construction and mode of operation, what I claim and desire to secure by Letters Patent of the United States, is as follows:

1. In or for a slug-casting machine, a composite mold having hardened steel side walls, and reinforcing members applied to the side walls and serving to resist warping or distortion thereof.

2. In or for a slug-casting machine, a composite mold having hardened steel walls and unhardened steel reinforcing members applied to said walls.

3. A mold body comprising a hardened steel base portion and an unhardened steel reinforcing member secured thereto.

4. A mold cap comprising a hardened steel base portion and an unhardened steel reinforcing member secured thereto.

5. In or for a slug-casting machine, a composite mold having hardened steel side walls of substantially uniform cross-section, and reinforcing members applied to the side walls to resist warping or distortion thereof.
6. In the method of manufacturing slug-casting molds, forming the mold cap and mold body each in two steel sections, one an inner base portion and the other an outer reinforcing portion, and hardening the base portions without hardening the reinforcing portions.
7. In the method of manufacturing slug-casting molds, forming the side walls of the mold cavity of hardened steel, and applying to said side walls reinforcing portions of unhardened steel.
8. In the method of manufacturing slug-casting molds, providing inner steel base portions to constitute the side walls of the mold cavity and separate outer steel reinforcing portions for application to said base portions, hardening the base portions, and leaving the reinforcing portions unhardened, for the purpose described.

In testimony whereof, I have affixed my signature hereto.

RICHARD R. MEAD.

Certificate of Correction.

It is hereby certified that in Letters Patent No. 1,569,386, granted January 12, 1926, upon the application of Richard R. Mead, of Brooklyn, New York, for an improvement in "Slug-Casting Molds," an error appears in the printed specification requiring correction as follows: Page 1, in the heading, names of patentee and assignee, strike out lines 3 and 4 and insert instead *Richard R. Mead, of Brooklyn, New York, assignor to Mergenthaler Linotype Company, a Corporation of New York.*; and that the said Letters Patent should be read with this correction therein that the same may conform to the record of the case in the Patent Office.

Signed and sealed this 9th day of February, A. D. 1926.

[SEAL.]

WM. A. KINNAN,
Acting Commissioner of Patents.
